APPARATUS FOR DRAWING METAL

Ernest H. Arnold, Cleveland, Ohio

Application August 4, 1931, Serial No. 555,023

14 Claims. (Cl. 113—46)

This invention relating as indicated to apparatus for drawing metal, has particular reference to apparatus for transforming a substantially circular flat blank of suitable metal into a cylindrical vessel having a closed bottom.

When converting a circular blank of relatively thin stock into a cylindrical body having a closed bottom it is necessary to progressively distort the metal by easy stages so that the resultant product will have a uniform wall thickness throughout, and, further, be free from wrinkles and other objectionable imperfections.

It is among the objects of my invention to provide apparatus for drawing metal which shall be capable of accomplishing the above named desirable results. Other objects of my invention will appear as the description proceeds. To the accomplishment of the foregoing and related ends, said invention, then, consists of the means 20 hereinafter fully described and particularly pointed out in the claims.

The annexed drawings and the following description set forth in detail certain means and one mode of carrying out the invention, such disclosed means and mode illustrating, however, but one of various ways in which the principle of the invention may be used.

In said annexed drawings:

Fig. 1 is a transverse sectional view of one form of the apparatus comprising my invention; Fig. 2 is a sectional view of a portion of the apparatus illustrated in Fig. 1, showing the relative position of the parts at the completion of the second draw; Fig. 3 is a transverse sectional view of a slightly modified form of apparatus in position to proceed with the third drawing operation; Fig. 4 is a sectional view of the apparatus illustrated in Fig. 3 showing the parts occupying the position at the completion of the fourth draw; Fig. 5 is a plan view of one of the forming ring supporting members forming a part of the apparatus illustrated in Figs. 1 and 2; Fig. 6 is a fragmentary side elevational view of a portion of the apparatus illustrated in Fig. 5; Fig. 7 is a perspective view of the means for removably securing the member illustrated in Fig. 5 in position to support one of the forming ring members of the apparatus illustrated in Figs. 1 and 2 and Fig. 8 is a perspective view of the cam block.

Referring now more specifically to the drawings and more especially to Fig. 1, the method comprising my invention and the apparatus for carrying forth the same forms a part of an entire machine assembly which includes a supporting base or table 1 and means associated with a

reciprocating head 2 whereby such head may be moved toward and away from the base 1. Since the entire mechanism forms no part of this invention and the construction of the same is well known to those familiar with the art, a showing of the detailed construction of such entire mechanism has been omitted in order to simplify the showing of the apparatus comprising my invention. Suffice it to say that the table 1 has associated therewith and supports, in the manner presently to be described, the actuated elements 5 of the apparatus which cooperate with the dies carried by the head 2.

Associated with the table 1, as most clearly illustrated in Fig. 1 is a cylinder 3 to which fluid under pressure may be supplied by means of a conduit 4 and a duct 5. Oscillatably supported in the cylinder 3 is a piston 6 which has associated therewith a vertically disposed piston rod 7. Concentric with the cylinder 3 is a second cylinder 8 which is supplied with fluid under pressure through the passage 8' and has associated therewith a piston 9 through which the piston arm 7 extends, pressure fluid admitted at duct inlet 8' having access to the piston 9 through any suitable communicating opening p. The piston rod 7 carries a head 10 and the piston 9 carries a head 11, which heads, in combination with the pistons associated therewith, suitably support the apparatus presently to be described.

The base 1 of the machine, or any other suitable part thereof, has preferably rigidly secured thereto a bed plate 12. Mounted on the bed plate 12 is a base member 13 which has centrally secured thereto and upwardly projecting therefrom 35 a forming stake or a male die 14, the outside diameter of which is equal to the inside diameter of the shell which is to be formed at the end of the second drawing operation.

The head 11, which is supported on the piston 40 9, carries a plurality of vertically disposed circumferentially spaced supporting pins 15 which at their upper ends carry an aligning and drawing plate 16. The plate 16 is concentric with the drawing stake 14 and has an annular ridge 17 45 formed thereon for the purpose of locating a suitable circular blank 18 of flat metallic stock from which the article is to be made.

Concentric with the forming stake 14 and the plate 16 and intermediately thereof is a forming 50 ring 19 which is axially supported for axial movement relatively to the forming stake 14 by an annular plate 20. The annular plate 20 which supports the forming ring 19 is in turn supported on the head 10 of the piston rod 7 by means of 55

a plurality of stakes or rods 21 arranged vertically and preferably equally spaced about the central forming stake.

The base member 13 has associated therewith an abutment 22, the form of which is most clearly illustrated in Fig. 7. The abutment 22 has a groove 23 formed in its upper surface in which is reciprocably mounted a cam block 24. The cam block 24 is movably secured in the groove 23 by means of a plate 25 which extends across such groove and is secured to the legs thereof. The outside end of the groove 23 is closed by a removable plate 26. Positioned within a recess provided therefor in the cam block 24 is a compression spring 27 which at one end bears against the inner face of the plate 26, and accordingly urges the cam block toward the annular plate 20. Excessive movement of the cam block 24 under the influence of the spring 27 is prevented by means of a pin 28 which is secured to the plate 25 and projects through the same into a slot 29 formed in the upper face of the cam block 24. The inner end of the cam block 24 carries on its upper face a narrowed vertical projection 31' which fits a slot in the rim of annular plate 20 positioned vertically through the middle of a recess 30 therein, next to be described.

The annular plate or ring 20, as most clearly illustrated in Figs. 2 and 5, is provided with a radial recess 30 for the reception of the horizontal ears 30' carried on the terminal portion 31 of the cam block 24, whereby such ring is locked in an elevated position, as most clearly illustrated in Figs. 1, 5 and 6. The ring member 20 likewise has spaced lugs 32 projecting radially therefrom which are adapted to engage the under face of complementary lugs 33 carried by the abutment 22. The lugs 32 and 33 cooperate to prevent the piston rod 7 from pushing the ring 20 upwardly 40 farther than the plane determined by such abutments.

The ring or plate 16 carries a cam punch 34 which, as such ring is lowered, moves the cam block 24 to the left, as illustrated in Fig. 1, against the spring 27 thereby releasing the engagement between the abutment 22 and the ring 20. For this operation a cam face on said cam punch 34 engages the inside end of said cam block 24.

The female die carried by the reciprocating head 2 of the machine consists of annular members 35 and 36 with inside diameters respectively equal to the outside diameters of the ring 19 and the forming stake 14 plus two thicknesses of the metal forming the article. The operation of the apparatus so far described is as follows:

When the parts are in the position illustrated in Fig. 1, a circular flat blank 18 of suitable material will be placed on the plate 16 and maintained in proper centered position by means of the annular projection 17. The female die is then brought down and the lower face 37 of the ring 35 presses the blank against the plate 16, which plate, as the female die descends, will likewise descend against the pressure exerted thereon by the piston 9.

As the die descends the ring 35 will draw the blank around over the forming ring 19 which is being rigidly supported in elevated position by annular ring 20 which is locked by means of the cam block 24 which engages the recess 30 in said ring 20. The metal is therefore smoothly drawn over the ring 19 until the cam punch 34 has descended sufficiently to move the cam block 24 out, thereby releasing the ring 20 which supports the

draw ring 19. As the female die descends further the size of the blank is reduced to that illustrated in Fig. 2. As the metal is drawn over the forming stake 14 the upper end of the drawing ring 19 forces the metal against the cam shoulder 33 by the force which is exerted on the ring 20 by means of the piston 6. The metal is therefore drawn to the size illustrated in Fig. 2 without possibility of the occurrence of wrinkles or like imperfections. The position of the several parts after the completion of this second drawing operation is most clearly illustrated in Fig. 2.

For a further reduction in diameter of the shell and a corresponding increase in its axial extent, an apparatus similar to that described and illustrated in Figs. 1 and 2 may be employed with the exception that a suitable ring member must be employed instead of the plate 16 for locating the blank centrally on the forming stake and maintaining suitable contact with the female die to prevent the occurrence of wrinkles during the drawing operation.

Such a form of apparatus, that is for the purpose of proceeding with the drawing operations after the circular flat blank has been cupped in the manner described, is most clearly illustrated in Figs. 3 and 4. In these figures is likewise illustrated an alternative form of construction of the means which may be employed for holding the draw ring in locked elevated position during the time the first drawing operation proceeds.

The apparatus illustrated in Figs. 3 and 4 is similar to that illustrated in Figs. 1 and 2 in that a central forming stake 14' is employed which is supported on a suitable base 13'. Pins or stakes such as 15' and 21' are employed with cylinders such as are illustrated in Fig. 1 for the purpose of maintaining suitable pressure on the draw rings to force the same into engagement with the female dies during the drawing operation to prevent the occurrence of wrinkles.

As previously indicated, the apparatus which is designed to operate on previously formed shells such as the product of the operations outlined in connection with the description of Figs. 1 and 2, the outer draw ring is in the form of an annular band 39 which is supported on a plate such as 16'. The ring 20' which supports the inner draw ring 19' in this modified form of construction, carries reciprocating slides 40 which are adapted to actuate reciprocating slides 41 mounted in suitable ways or guides provided therefor in the central forming stake 14'. The slides 41 are normally urged outwardly or radially of the forming stake by means of a compression spring 42 which, when the ring 20' is in the position illustrated in Fig. 3, forces the slides 41 outwardly so that the ring 19' is locked against downward axial movement on the stake 14'. As the female die moves downwardly and after the first draw has been completed, by forcing the plate 16' downwardly the cam punches 34' will force the slides 40 and therethrough push the slides 41 inwardly until the outer ends of the slides 41 are flush with the outer periphery of the forming stake 14' so that the forming ring 19' may move downwardly as the last drawing operation is performed by the female die 33' in forcing the metal of the shell down over the central forming stake. The position of the several parts after this last draw has been completed is most clearly illustrated in Fig. 4.

From the above description it will be noted that metal may be formed by my invention by first

providing a substantially circular blank of flat metallic stock and then successively forming the same in the manner described. This may be done with the apparatus comprising my invention with a minimum number of operating parts. A further advantage of the apparatus comprising my invention resides in the fact that the entire actuating mechanism for the means rigidly supporting the intermediate forming ring during the first drawing operation is entirely contained within the apparatus associated with the dies. It is therefore necessary only to provide a set of dies with the associated mechanism as above described with any of the well known types of machines for drawing metal, and the superior results above enumerated can be attained by the simple operation of the described parts.

Other modes of applying the principles of my invention may be employed instead of the one explained, change being made as regards the means and the steps herein disclosed, provided those stated by any of the following claims or their equivalent be employed.

I therefore particularly point out and distinctly claim as my invention:

1. In apparatus of the character described, the combination of a female die, a plurality of male dies, means resiliently supporting some of said male dies, radially movable locking means securing one of said male dies against movement, and means movable with another of said male dies for releasing said locking means.

2. In apparatus of the character described, the combination of a female die, a plurality of relatively movable concentrically arranged male dies, means resiliently supporting some of said male dies, radially movable locking means securing one of said male dies against movement, and means movable with another of said male dies for releasing said locking means.

3. In apparatus of the character described, the combination of a female die, a plurality of relatively movable concentrically arranged male dies the central one of which is stationary, means resiliently supporting some of said male dies, radially movable locking means securing one of said male dies against movement, and means movable with another of said male dies for releasing said locking means.

4. In apparatus of the character described, the combination of a female die, a rigidly supported male die, a plurality of annular male dies concentric with said rigid male die, fluid actuated means supporting said annular dies, radially movable locking means for one of said annular dies, and means carried by another of said annular male dies for engagement with said locking means to render the same inoperative.

5. In apparatus of the character described, the combination of a female die, a rigidly supported male die, a plurality of annular male dies concentric with said rigid male die, fluid actuated means independently resiliently supporting said annular dies, radially movable locking means for one of said annular dies, and means carried by another of said annular male dies for engagement with said locking means to render the same inoperative.

6. In apparatus of the character described, the combination of a female die, a fixed male die, a plurality of annular male dies slidably mounted on said fixed die, air cushions supporting each of said annular dies, radially movable means locking one of said annular dies against movement relatively to said fixed die, and means

movable with another of said annular male dies for releasing said locking means.

7. In apparatus of the character described, the combination of a female die, a fixed male die, a plurality of annular male dies slidably mounted on said fixed die, air cushions supporting each of said annular dies, radially movable means locking one of said annular dies against movement relatively to said fixed die, and a cam punch movable with another of said annular male dies for releasing said locking means.

8. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, means for resiliently supporting said forming die, radially movable locking means for rigidly supporting said forming die, and means carried by said resilient supporting means for releasing said locking means.

9. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means and positioned intermediate thereof, fluid actuated means resiliently supporting said forming die, radially movable locking means for said forming die and means carried by said blank-supporting means for releasing said locking means.

10. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, fluid actuated means resiliently supporting said forming die, an abutment adjacent said forming die, radially movable locking means associated with said abutment for engagement with said forming die, and a cam member dependent from said blank supporting means arranged to move said locking means into releasing position.

11. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, fluid actuated means resiliently supporting said forming die, an abutment adjacent said forming die, radially movable means associated with said abutment arresting axial movement of said forming die, and means carried by said blank supporting means arranged to release said radially movable means arresting movement of said forming die in one direction.

12. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, fluid actuated means

resiliently supporting said forming die, an abutment adjacent said forming die, radially movable means associated with said abutment arresting axial movement of said forming die, and means immediately associated with said blank supporting means arranged to release said radially movable means arresting movement of said forming die in the same direction as said female die.

10 13. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, fluid actuated means resiliently supporting said forming die, radially 15 slidable locking means for said forming die supported in said forming stake, and cam means

carried by said blank supporting means for moving said locking means into releasing position.

14. In apparatus of the character described, the combination of a movable female die having axially adjacent sections of different diameters, a fixed forming stake, resilient supporting means concentric with said stake for locating and supporting the blank to be operated upon, a forming die concentric with said stake and blank supporting means, fluid actuated means 10 resiliently supporting said forming die, radially movable locking means for said forming die within said forming stake, slides movably supported by said forming die for actuating said locking means, and cam means dependent from 15 said blank-supporting means for actuating the lock releasing slides supported by said forming die.

ERNEST H. ARNOLD.
